UNITED STATES PATENT OFFICE.

JULIUS S. MEYER, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,676, dated February 27, 1883.

Application filed January 25, 1883. Term of patent 3½ years.

To all whom it may concern:

Be it known that I, JULIUS S. MEYER, of New York city, in the State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is filled in with small diagonally-arranged figures, with larger geometric, fan-like, and circular figures occurring at irregular intervals. On this ground are four flower groups, A, B, C, and D, each consisting of central flower and leaf masses, with projecting sprays bearing flowers and blossoms.

The design as a whole presents an open appearance.

I claim—

1. The design for a ground for a carpet, consisting of the ground *a*, substantially as shown and described.
2. The design for a carpet, consisting of the group A, substantially as shown and described.
3. The design for a carpet, consisting of the group B, substantially as shown and described.
4. The design for a carpet, consisting of the group C, substantially as shown and described.
5. The design for a carpet, consisting of the group D, substantially as shown and described.
6. The design for a carpet, consisting of the groups A, B, C, and D, substantially as shown and described.
7. The design for a carpet, consisting of the groups A, B, C, and D and the ground *a*, substantially as shown and described.

JULIUS S. MEYER.
